UNITED STATES PATENT OFFICE.

PHILIP T. DODGE, OF NEW YORK, N. Y., ASSIGNOR TO MERGENTHALER LINOTYPE COMPANY, A CORPORATION OF NEW YORK.

TYPOGRAPHICAL MACHINE.

1,151,572.

Specification of Letters Patent. Patented Aug. 31, 1915.

Application filed September 22, 1914. Serial No. 862,878.

To all whom it may concern:

Be it known that I, PHILIP T. DODGE, a citizen of the United States, residing at New York, in the county of New York and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States No. 436,532, to O. Mergenthaler, wherein circulating 15 matrices are released from a magazine or magazines in the order in which their characters are to appear in print and then assembled in line, the composed line transferred to the face of a mold, the mold filled 20 with molten metal to form a slug or linotype against the matrices which produce the type characters thereon, and the matrices thereafter returned by distributing mechanism through a channeled magazine entrance to the magazine or magazines from 25 which they started.

More particularly, it relates to the magazine entrance and involves the provision of means whereby the width of certain of its 30 channels may be varied at will throughout their length, to adapt them to matrices of different size and thickness.

In the accompanying drawings, I have shown my invention in preferred form, and 35 as applied to a "Model 8" linotype machine, but obviously many changes and variations may be made therein, and in its mode of application, which will still be comprised within its spirit. Similarly, it may be adapted 40 to other forms of typographical machines, such as typesetters, typecasters and the like, which handle type or dies, instead of matrices. Generally speaking, I desire it to be understood that I do not limit myself to 45 any specific form or embodiment, except in so far as such limitations are specified in the claims.

Referring to the drawings: Figure 1 is a side view of a portion of the machine, 50 having my invention embodied therein; Fig. 1^a is a detail; Fig. 2 is a vertical section, on an enlarged scale, through the magazine entrance, etc.; Fig. 3 is a section on the line 3—3 of Fig. 2; and Fig. 4 is a similar view 55 showing the parts in different position.

The matrices are stored as usual in their proper magazines A, three being shown by way of example, the magazines being movably arranged so that through the connections A¹ and handle A², any selected one 60 may be brought into operative relation to the assembler raceway B and distributing mechanism C, from which the matrices are returned to the magazine through the channel entrance D.

65 The parts so far described are or may be of any suitable construction, such for instance as that embodied in the Model 8 linotype, and in themselves constitute no part of my present invention, except as subsequently indicated.

70 In multiple magazine machines of the kind referred to it is common practice to provide one or more magazines with their matrix channels or grooves widely spaced 75 apart, so that a limited number of large matrices may be carried therein and delivered therefrom in the ordinary manner; and also the same results are sometimes obtained by locating the large matrices in alternate channels of an ordinary magazine and leaving the intermediate channels unoccupied. In either case the channels of the magazine entrance must be widened to correspond, and to effect this result I have provided means whereby some of the partitions 80 are adjustably arranged to permit their shifting toward and from adjoining partitions.

85 Referring to Figs. 2, 3 and 4, it will be seen that the partitions are divided into two sets, one E connected to the fixed frame G, and the other set F alternately disposed with relation to the fixed partitions and connected to the laterally shiftable frame H. 90 Fig. 3 shows the parts in normal condition, namely, with the usual spacing between the partitions E and F of the respective sets, and the magazine entrance therefor adapted to permit the passage of the ordinary matrices X. Fig. 4 illustrates the frame H as shifted laterally and to an extent sufficient 95 to move the connected partitions F into contact with the fixed partitions E, thus substantially doubling the width of the entrance channels and adapting them to the passage of the large or thick matrices X¹.

100 The means for effecting the lateral adjustment of the shift frame may be of any desired character. In my preferred form 110

they comprise the longitudinally movable stem J connected to the frame H, and the spring K to hold the frame and the partitions F in normal position (Fig. 3). To move the frame H to other positions, and against the pressure of the spring K, I employ an eccentric L contacting with the stem J and mounted upon the operating rock shaft M, in such manner that the rotation of the latter effects the desired adjustment. The opposite end of the shaft M (Fig. 1) is located at the front of the machine and within easy reach of the operator at the keyboard, and is preferably provided with an operating wheel or handle N, and with an indicator O (Fig. 1^a) to show the adjusted position of the channel partitions.

As previously stated, I have shown my invention only in preferred form and by way of example, and in a special mode of adaptation. However, many modifications and alterations therein, and in the mode of application, will suggest themselves to those skilled in the art, without departure from its scope.

Having thus described my invention, its construction and mode of operation, what I claim and desire to secure by Letters Patent of the United States, is as follows:

- 30 1. In a typographical machine, the combination of a magazine entrance having a series of channels, and means whereby the width of certain of said channels may be varied at will throughout their length.
- 35 2. A magazine entrance for typographical machines having a series of partitions forming channels between them, certain of said partitions being adjustable bodily toward and from adjoining partitions, to vary the width of the intermediate channels throughout their length.
- 40 3. A magazine entrance for typographical machines having a series of partitions forming channels between them, certain of said partitions being movable bodily from their normal positions to provide a reduced number of channels of increased width.
- 45 4. A magazine entrance for typographical machines having a series of partitions forming channels between them, certain of said partitions being movable up against adjoining partitions to increase the width of the intermediate channels throughout their length.
- 50 5. A magazine entrance for typographical machines having a series of partitions forming channels between them, and means for moving the alternate partitions up against the adjoining ones; whereby the channels may be reduced in number and increased in width.
- 55 6. A magazine entrance for typographical

machines having a series of partitions forming channels between them, the alternate partitions being movable as a whole from their normal positions to reduce the number of channels in the entrance and to increase them in width.

7. In a typographical machine, the combination of a magazine entrance having a series of partitions forming channels between them, and an adjustable frame connected to certain of said partitions for moving them as a whole toward and from adjoining partitions, for the purpose described.

8. In a typographical machine, the combination of a magazine entrance having a series of partitions forming channels between them, an adjustable frame connected to certain of said partitions for moving them bodily toward and from adjoining partitions, and operating devices connected to said frame and extending to the front of the machine.

9. In a typographical machine, the combination of a magazine entrance having a series of partitions forming channels between them, an adjustable frame connected to certain of said partitions for moving them bodily toward and from adjoining partitions, operating devices connected to said frame and extending to the front of the machine, and an indicator connected to said operating devices to show the adjusted position of the frame.

10. In a typographical machine, the combination of a magazine entrance having a series of channels, means for varying the width of certain of said channels throughout their length at will, and an indicator to show the condition of said entrance.

11. In a typographical machine, the combination of a magazine entrance having a series of partitions, certain of which are adjustable bodily toward and from adjoining ones, and an indicator to show the adjustment of said partitions.

12. In a typographical machine, the combination of a magazine entrance having a series of partitions forming channels between them, means for adjusting certain of said partitions bodily toward and from adjoining ones to vary the width of the intermediate channels, and operating devices for said means extending to the front of the machine within reach of the operator at the keyboard.

In testimony whereof, I have affixed my signature in presence of two witnesses.

PHILIP T. DODGE.

Witnesses:

WALTER NOBLARD,
E. J. LAMB.
